United States Patent Office

Des. 196,568
Patented Oct. 15, 1963

196,568

BUILDING FRONT

Jose M. Figueras, Manila, Republic of the Philippines,
assignor to Overseas International, Inc., Redwood City,
Calif., a corporation of California

Filed Dec. 17, 1962, Ser. No. 72,881

Term of patent 14 years

(Cl. D13—1)

FIG. 1.

FIG. 2.

FIG. 1 is a front elevational view of a building front showing my new design.

FIG. 2 is a perspective view in reduced scale thereof. The broken lines showing a building in FIG. 2 are for illustrative purposes only.

I claim:

The ornamental design for a building front, as shown and described.
